UNITED STATES PATENT OFFICE.

WALTER W. WINIARSKI, OF BUFFALO, NEW YORK.

ORTHOPEDIC APPLIANCE.

1,356,327.

Specification of Letters Patent. Patented Oct. 19, 1920.

Application filed February 17, 1919. Serial No. 277,596.

To all whom it may concern:

Be it known that I, WALTER W. WINIARSKI, a citizen of the United States, residing at Buffalo, in the county of Erie and State of New York, have invented certain new and useful Improvements in Orthopedic Appliances, of which the following is a specification.

This invention relates to improvements in orthopedic appliances, and more particularly to a brace or support for a fractured or deformed limb, used either to maintain the limb in proper form or to relieve the same from the weight of the body, depending upon the particular use to which the invention is applied.

In the particular adaptation of my invention shown, it is intended to impart the weight of the body from a fractured lower leg portion to the brace or support and incidentally assist the foot in its natural action while walking, thereby relieving the fracture from strain so as to permit the injured limb to become properly healed within the shortest period of time without causing inconvenience to the injured person.

While I have shown this invention embodied in an appliance adapted for fractured limbs, it will be apparent that it may be used on any appliance adapted to be in part attached to the shoe of the wearer, either for the purpose shown or for correcting any deformity of the leg.

One of the objects of my invention is to provide means for detachably securing orthopedic appliances to a shoe.

Another object is to provide a simple and effective orthopedic appliance adapted for relieving a wounded leg from strain, or for correcting any deformities while permitting the user to wear any desired shoe in connection with the appliance.

The invention consists in the novel features of construction, and in the arrangement and combination of parts to be herein-after described and more particularly pointed out in the subjoined claims.

In the drawings:

Figure 1 is a perspective view illustrating 50 the application of this invention.

Fig. 2 is a detached perspective view of the lower portion of an orthopedic appliance constructed according to my invention.

Fig. 3 is a cross section taken on a plane indicated by the line 3—3, Fig. 2. 55

Referring by reference numerals to the drawings, 4 designates an appliance, such as is adapted for application to a limb fractured below the knee, and it comprises a leg-band 5 adapted to be fastened around the leg of the user in any suitable manner. A brace or support 6 is secured to the leg-band 5 and extends downwardly therefrom to the sole of the shoe 7, to which is detachably secured in the manner to be hereinafter 60 set forth. The brace or support comprises an upper brace member 8 which extends downwardly from the leg-band 5 to a point in line with the ankle-joint where it is pivotally secured to a lower brace member 9, 70 as at 10.

The upper brace member 8 is preferably constructed of thin bar material, while the lower brace member 9 is preferably stamped from sheet metal with a lug 11 formed 75 thereon and twisted at a right angle to the face of said lower brace member. In all appliances of this kind the lower brace member is secured to the shoe of the wearer, either directly or through the medium of 80 another member or part, and in all instances the attachment is made permanent so that the same shoe must be worn with the appliance at all times.

Appliances of this kind are invariably 85 provided with means to prevent drooping of the front portion of the foot when raising the leg during the action of walking, such means being arranged so that the front portion of the foot may be raised during the 90 walking action, but for this purpose I have provided novel means including the lug 11 which has a rod 12 passed through an opening 13 in said lug, said rod having its upper end passed through a second lug 14 extending forwardly from the front edge of the upper brace member 8, both upper and lower extremities of said rod being threaded, as at 15, with a nut 16 applied to each threaded end and in contact with the under 100 and upper sides of the lugs 11, 14, respectively. Consequently, when raising the front portion of the foot upwardly while walking, the lug 11 may move upwardly on the rod 12, and when stepping forward 105 said lug may move downwardly on said

rod until the under side thereof again comes in contact with the nut 16, thus limiting the drooping movement of the front portion of the foot and relieving the fracture from 5 undue strain.

In the event of its being found that the necessary freedom of the foot is not provided for during the walking action, the lower nut 16 may be lowered on the rod or 10 the upper nut 16 raised, which will permit the front portion of the foot to droop to a slightly greater degree, but when the drooping action is found to be too great and causes the fractured portion of the leg to be 15 strained, such action may be restricted by threading the lower nut 16 upwardly or the upper nut 16 downwardly on the rod 12. It will be noted that the lug 11 extends forwardly and slightly inwardly over the front 20 of the foot so that its restraining action is in the plane of the front portion of the foot, the action of which it is adapted to control.

It is apparent that the nuts 16 serve as stop enlargements, and therefore, if desired, 25 the upper or lower end of the rod 12 may have a fixed head or enlargement since the adjustment may be effected satisfactorily at one end of the rod.

The lower brace member 9 is widened as 30 it closely approaches the arch of the shoe, as at 17, and is then bent inwardly, as at 18, with its inner extremity bent downwardly to form a securing flange 19. Secured to the inwardly bent portion of the 35 lower brace member is a securing element or clamp whereby the lower portion of the appliance is detachably secured to a shoe. This securing element or clamp comprises two members 20, 21, of which member 20, in 40 the preferred form of appliance shown, is permanently secured to the widened inwardly bent portion 18, of the lower brace member 9. Member 20, which is preferably wider and longer than member 21, as best 45 shown in Fig. 2, has a flat bearing portion 22 of substantially the same width and length as the inwardly bent portion 18 of the lower brace member 9, a downwardly bent flange 23 which lies in contact with the 50 inner face of the securing flange 19, and an upwardly and inwardly curved clamping portion or retainer flange 24 at its outer marginal portion, which is extended rearwardly, as at 24^a. This clamping portion or 55 retainer flange is adapted to engage or embrace the edge of the shoe-sole at the arch of the shoe, and the rearwardly extended portion 24^a thereof is adapted to be partly embedded between the shoe upper and the 60 heel, as at 24^b, Fig. 1, or into the body portion of the heel, as may be desired.

Member 20 is preferably secured to the widened inwardly bent portion 18 of the lower brace member by means of rivets 25, and member 21, which is narrower and

shorter than member 20 of the securing element or clamp, comprises a flat upper portion 26, a downwardly bent flange 27 at the inner marginal portion of said flat upper portion and an upwardly and inwardly curved clamping portion or retainer flange 28 at the outer marginal portion thereof, which is extended rearwardly, as at 28^a. This rearwardly extended portion 28^a is also adapted to be partly embedded between the 75 shoe upper and the heel, or into the body of the heel, as may be desired.

The downwardly-directed flange 27 is adapted to lie in contact with the inner face of the flange 23 of member 20, so that the three flanges 19, 23 and 27 are arranged in contact one with another, and through these three flanges, one or more screws 29 are passed, the screw or screws being passed loosely through openings in the flanges 19 and 23, and threaded into an opening or openings in the flanges 27. These flanges may, however, be otherwise fastened together. Member 21 of the securing portion of the appliance is therefore removable 90 from the remainder of the appliance, and upon loosening the screws 29, the appliance may be detached from the shoe of the wearer. This may be accomplished without removing the appliance from the leg of the 95 wearer so that the wearer may, for different occasions, change his shoe and quickly and conveniently secure the appliance thereto.

By making the securing element or portion of the appliance in two parts, one of 100 the parts or members, viz., the detachably-secured part or member 21, may be a replaceable part or member; that is to say, the part or member 21 may be manufactured in large quantities and in different widths, 105 while the part or member 20 may always be of the same width, thus enabling a narrower or wider part or member 21 to be connected to the part or member 20, as the width of the shoe to which the appliance is to be attached 110 may require.

By the use of the rearwardly extending portions 24^a and 28^a for coöperation with the heel of a shoe, the brace or support 6 is given a firm bearing when the heel is in 115 contact with the floor, whereas if the securing element or clamp were made to coöperate only with the sole at the arch of the foot, it would be permitted to yield owing to the fact that there is nothing underneath 120 the arch to prevent its downward movement. The coöperation therefore of this brace or support with the heel is a decided advantage in the use of this invention.

When using shoes in connection with this 125 appliance which have the arch portions of the sole wider than the securing or clamping portion and it is not desired to replace the narrow part or member 21 with a wider part or member, a suitable filler strip may 130

be interposed between the two flanges 23 and 27, so as to increase the space between the upturned gripping flanges 24 and 28. When attached to a shoe, the securing element or portion is concealed, with the exception of the gripping flange 28, and securely fastens the lower portion of the appliance to the shoe.

This appliance may be said to comprise 10 two right angled parts, one having means to detachably fasten the same to the leg of the wearer and the other including means to detachably fasten it to a shoe at the arch portion thereof so that no portion of the appliance will come in contact with the ground or floor while walking, the appliance being arranged to permit flexing of the shoe while walking.

Having thus described my invention, what 20 I claim is:—

1. An orthopedic appliance comprising a leg-band, a brace or support having its upper end secured to said leg-band and having two pivotally connected members with the 25 lower end of one of said members attached to the shoe, said last-mentioned member having an extension provided with an opening, a rod having its upper end secured to the upper portion of the appliance and extending 30 downwardly through the opening in said extension, and adjustable means on said rod adapted to engage said extension.

2. An orthopedic appliance comprising a leg-band, a brace or support extending 35 downwardly from said leg-band and having two pivotally-connected members with the end of one of said members secured to the shoe, said last-mentioned member having a forward extension provided with an opening, a rod secured at its upper end to said appliance at a point above said forward extension and extending therefrom downwardly through the opening in said extension, the lower end of said rod being threaded, and a nut adjustably applied to the 45 threaded lower end of said rod and bearing against the under side of said forward extension.

3. An orthopedic appliance comprising a 50 body portion having an inwardly-bent lower end adapted to extend underneath the arch of a shoe, a securing portion comprising two members, one of said members being secured to the inwardly-bent lower end of said body portion and the other member being detach-

ably secured to the first-mentioned member to co-act with the latter for detachably securing the lower end of said body portion to the shoe.

4. An orthopedic appliance comprising a 60 leg-band, a body portion secured to said leg-band and extending downwardly therefrom, the lower end of said body portion being bent inwardly and having a gripping element thereon adapted to engage one edge 65 of the sole of a shoe, and a detachable member applied to the lower end of said body portion and having a gripping element adapted to engage the other edge of said sole.

5. An orthopedic appliance comprising a leg-band, a brace or support extending downwardly from said leg-band and having a widened lower end bent inwardly and terminating in a downwardly bent securing 70 flange, a securing portion comprising two members, one of said members having a flat portion lying in contact with the upper face of the inwardly bent portion of said body portion and having a downwardly bent securing flange at its inner marginal portion in contact with the securing flange of said body portion and an upwardly bent gripping flange at its outer marginal portion adapted to engage one edge of the sole of a 75 shoe, the other member of said securing portion comprising a flat portion having a downwardly bent securing flange at its inner marginal portion lying in contact with the securing flange of the first-mentioned 80 member of said securing portion and an upstanding gripping flange at its outer end to engage the opposite edge of the sole of the shoe, and detachable fastening means 85 for securing said securing flanges together.

6. An orthopedic appliance comprising a body portion, a gripping element secured to the lower end of said body portion to engage one edge of the sole of a shoe and with its rear end engage one side of the heel of the shoe, and a detachable member applied to the lower end of said body portion and having a gripping element adapted to engage the other edge of said sole, said gripping element having its rear portion adapted to engage the other side of the heel of the shoe.

In testimony whereof I affix my signature.

WALTER W. WINIARSKI.
